D. A. JAMES

WAISTBELT

Filed April 17, 1922

Fig. 2.

Fig. 9.

A detailed technical drawing of a curved railway track. The track is shown in perspective, curving from the left towards the right. Several labels are present: 'A' is at the top left, 'B' is at the top center, 'B'' is at the top right, and 'f'' is repeated multiple times along the bottom curve. The drawing includes various mechanical components like a switch mechanism and a wheel set.

conveniunt.

By his Attorney, David A. James,
Geo. F. Math,

Patented Dec. 4, 1923.

UNITED STATES PATENT OFFICE.

DAVID A. JAMES, OF NEW YORK, N. Y.

WAISTBELT.

Application filed April 17, 1922. Serial No. 553,885.

To all whom it may concern:

Be it known that I, DAVID A. JAMES, a citizen of the United States, and a resident of the borough and county of Bronx, city 5 and State of New York, have invented certain new and useful Improvements in Waistbelts, of which the following is a specification.

My improvements relate to waist or body 10 belts of the expandible and contractable type, and are designed to simplify and cheapen the construction thereof, while rendering such belts more durable, convenient, and comfortable for wear.

With these objects in view, my invention 15 consists in the specific construction, combination and arrangement of parts and appurtenances herein described and claimed, whereby I attain what may be designated as 20 a "telescopic" effect,—distinctive features of the structure, considered in a unitary sense, being a slidable connection or coupling member between the belt sections; and the fact that the elastic resilient portions thereof are 25 detachable and replaceable, substantially as hereinafter fully set forth,—an incidental feature being the constructing of the coupling slide member out of a single piece or blank.

In the accompanying drawings, I exemplify a practical embodiment of the essential features of my invention, although I do not wish to limit myself to the identical form and construction of parts shown, since 35 various modifications may be resorted to, in so far as minor details are concerned, without departing from the spirit and intent of my invention.

Fig. 1, is a perspective view of my "telescopic" belt in closed form, with the ends buckled together in a manner well known in the art;

Fig. 2, is an elevation of one of my detachable elastic resilient replacements;

Fig. 3, is a section, upon an enlarged scale, taken upon plane of line 3—3, Fig. 1;

Fig. 4, is a transverse section taken upon plane of line 4—4, Fig. 3;

Fig. 5, is a view of the inner side of the 50 slidable coupling member, unattached to the belt sections;

Fig. 6, is a transverse section taken upon plane of line 6—6, Fig. 5;

Fig. 7, is a view of the blank from which 55 said slidable coupling member is formed;

Fig. 8, is a view of the main or medial por-

tion of the belt, opened up in slack condition, the better to show the parts and their correlation, the slidable coupling member being indicated in section;

Fig. 9, is a view similar to Fig. 2, illustrating a modification in the character of the elastic resilient medium employed.

My "telescopic" belt consists essentially of two straps A and B, of leather or other flexible non-elastic material, the first, A, which I will for convenience designate as the buckle strap, having the usual buckle a, attached to the outer end thereof, and the other, B, which for a like reason I will 65 designate as the tongue strap, formed with the usual series of holes b, b, for engagement with the tongue of the buckle a, said straps A, and B, being movable upon and with relation to each other and being coupled together by a slide member S; and also of two elastic resilient sections E, E', the one, E, attached to said coupling slide member S, and to the buckle strap A, and the other E', being connected with the inner end 70 of the buckle strap A, and to the tongue strap B. It is obvious however that an alternative or reverse arrangement of parts may be resorted to with like effect in that the coupling slide S, may be attached to the 75 buckle strap A and to the elastic resilient section E'.

The attachment of these elastic resilient sections E, E', to the parts named as above may be permanent if desired, as by sewing, 80 riveting or otherwise, but I prefer to make said elastic resilient sections E, E', detachable and replaceable by the use of snap fastenings consisting of studs f, f, and sockets f', f', after the manner of "glove fastenings" so called, and well known in the arts; in which case the ends of the elastic resilient sections E, E', are preferably formed with the sockets f', f', and the belt straps and copulative slide member S, with the studs 85 f, f, as shown in the drawings, although an alternative arrangement of such snap fastenings may be resorted to if desired with essentially like results in so far as the functions of said snap fastenings are concerned,—the main object being to render 90 said elastic resilient sections E, E', adaptable for use as replacements.

The yieldable portions of the elastic resilient sections E, E', may consist of rubber 110 fabric e, e', as in most of the figures of the drawings, or, as indicated in the modifica-

tion shown in Fig. 9 of one or more retractile springs e^2 , e^2 , secured medially between end portions e^x , e^x , provided with detachable securing means as hereinbefore set forth.

5 In either case the result is the same in that the elastic resilience of the replacement sections E, E', while yielding under stress of use, tend constantly to hold the component parts of the belt taut and to compensate for changes in body position. In other words, the belt, thus constricted, adapts itself automatically to the varying exigencies, conditions, and requirements of use without discomfort to the wearer.

10 15 In this respect the slidable coupling S, performs an important function in telescopically linking the several parts together in such manner that they are free to adapt themselves to both expansive and contractile stress with the least possible frictional resistance,—the strain being equally distributed throughout the whole structure.

While not necessarily so, the coupling slide S. is preferably made from a single 25 piece blank of suitable material, as indicated in Figs. 5, 6 and 7, the end extension 2, and the lateral side extensions 3, 3, of the medial portion 1, of said blank being bent over upon the latter. Thus the end extension 30 2, which is formed with indentations i , i , is bent over to clasp and hold the end of the belt strap to which it is permanently attached, the indentations i , i , acting as barbs to prevent the displacement of said strap 35 end, while the side extensions 3, 3, may be stamped and upset to form the snap studs f , f , for engagement with the sockets f' , f' ,

on the ends of the replacements E, or E', as the case may be, or said snap studs f , f , may be separately formed and affixed to the slide 40 S, as may be desired, or found most expedient in manufacture.

My telescopic belt is simple both in construction and operation, and durable in use because, as before stated, the strain is distributed equably between the several parts, the elastic resilient sections, of course, standing the brunt of wear, but as these are replaceable, the life and utility of the belt is extended indefinitely, because they may be 50 replaced as required with facility, and at small expense as compared with that which would be involved in the discarding of the entire belt.

What I claim as my invention and desire 55 to secure by Letters Patent is,

A "telescopic" belt of the character designated, comprising a non-elastic buckle strap, a non-elastic tongue strap, a coupling slide permanently attached to the end of one 60 of said straps and embracing the other strap, an elastic section detachably secured to one of said straps by snap fastenings and detachably secured to said coupling slide by snap fastenings, and another elastic section 65 detachably secured to both of said straps by snap fastenings, said coupling slide being formed in one piece with attachment barbs, and with snap studs, substantially in the manner and for the purpose set forth.

DAVID A. JAMES.
